UNITED STATES PATENT OFFICE

ANTONIO LOMBARDO, OF BROOKLYN, NEW YORK

AUTOMATIC BOMB-DROPPING DEVICE

Application filed February 10, 1928. Serial No. 253,294.

This invention relates to a new and useful device in the nature of an automatic bomb dropping device especially adapted for dropping bombs from aeroplanes, airships and 5 the like.

The object of the invention is to provide a device adapted to hold a plurality of bombs in combination with a manually operated means of releasing the said bombs as may be 10 desired.

A further object of the invention is to provide a device of the class described of novel construction and arrangement of parts hereinafter more fully described, claimed and illustrated in the accompanying drawing.

Fig. 1 is a perspective view of an aeroplane equipped with my improved device.

Fig. 2 is an enlarged front elevational view of my improved device.

20 Fig. 3 is a side elevational view thereof.

Fig. 4 is a top plan view thereof showing the cover removed so as to more clearly show the construction of my improved device.

Fig. 5 is a side elevational view of the bomb 25 release mechanism as embodied in my improved device showing same in an engaged position.

Fig. 6 is a top plan view thereof.

Fig. 7 is a similar view to that shown in 30 Fig. 5, illustrating the bomb release mechanism in a disengaged position.

Fig. 8 is a side elevational view of the bomb locking door as embodied in my improved device.

35 Fig. 9 is a fragmentary vertical sectional view taken on the line 9—9 of Fig. 8.

As here embodied my improved device comprises a container of box like construction consisting of a base 10, a cover 11 and sides 40 12 and 13. Brackets 14 and 15 are secured to the upper edges of the sides 12 and 13, respectively, as a means of attaching my improved device, in a suspended position to any suitable portion of an aeroplane, airship 45 or the like, as clearly shown in Fig. 1, in which I have shown my improved device secured to and suspended from the lower wing 16 of the aeroplane 17. It is obvious from the following description that my improved device must be secured to a portion of the plane,

such as will permit the bombs contained therein when released to fall clearly of the aeroplane, airship or the like, to which same is attached, so as to permit the said bomb to fall on the ground or any desired object for the purpose of bombing the said objective.

Vertical partitions 18 and 19 are secured to the base 10 and cover 11 and are positioned in proximity to the sides 12 and 13, respectively. End members 20, 21 and 22, 23 vertically disposed are secured to the base 10 and cover 11, and are adapted to form separate compartments 24 and 25, adapted to enclose or hold the bombs 26, 27 and 28, 29 respectively, which are positioned or arranged in a vertical pile in the said compartments.

The bomb locking doors 30 and 31 are slidably mounted in guide members 32, secured to the base 10, and are adapted to enclose the open portions of base 10, directly below the said compartments 24 and 25. The rods 33 are secured to the locking doors 30 and are horizontally extended therefrom and are slidably mounted in the brackets 34 secured to the under portion of the base 10. The rods 33 are provided with handle elements 35, formed or bent at approximately right angles to the main portions of the said rods. The expansion springs 36 are co-axial on the rods 33 and are secured as at 37 at one of their extremities to the said rods in proximity to the said locking doors, as a means of normally holding the said locking doors in a closed position, as a means of preventing the releasing of the bomb placed in the said compartments. The base 10, has formed therein openings 38 adapted to receive the handle elements 35 of the said rods 33, as designated by the reference numeral 39, as a means of holding the locking doors in an open position, so as to permit the bomb to be dropped when released by the mechanism as hereinafter described.

A plurality of bomb release mechanisms 95 consisting of supports 40 are slidably mounted in the brackets 41, secured as at 42, to the portions 18 and 19. A pair of engaging members 43 and 44 are pivotally secured as at 43' and 45, to the supports 40 and to the vertical 100

- extended elements 46 of the said supports. said supports so that the bombs are discharged. Tension springs 47 are secured to the engaging members 43 and 44 as a means of urging the said engaging members inwardly, as a means of supporting or holding the above mentioned bombs. The said engaging members 43 and 44 are normally held in horizontal extended position in the said compartments adapted to hold the above mentioned bomb by means of the tension springs 48 secured to the brackets 41 and to the supports 40, openings 49 and 50 are formed in the said portions adapted to slidably receive the said engaging members 43 and 44, respectively. 10 It is understood that a pair of the engaging members 43 and 44 are provided for each support, so as to securely hold the said bombs in position in the said compartments. Flexible members 51 are secured to the outer extended 15 extremities of the supports 40, and are extended therefrom over the rods 52, horizontally disposed and mounted on the supports 53 and 54 secured to the base 10 and the cover 11, and centrally positioned vertically in the 20 above mentioned container. The flexible members 51 are extended upwardly from the rods 52 through openings formed in the cover 11 and extended therefrom 53, suitably secured to any convenient suitable portion of 25 the aeroplane 17, and have secured thereto, at their extended extremities handles 54, positioned in convenient reach of the operator, observer or passenger of the said aeroplane. The above described construction is such as 30 will obviously permit the bombs to be released when the said handles are manually pulled by the operator, observer or passenger of the aeroplane. The said bomb release mechanism assuming the position as clearly 35 shown in Fig. 7, of the accompanying drawing. The above described construction also is such as will permit the engaging members 43 and 44, to strike the portions 18 and 19, as designated by the reference numerals 55 and 40 56, respectively, when the handle 54 is released for the purpose of preventing the bomb 45 release mechanism thus operated to interfere with the releasing of the bombs positioned above the bomb which has been released. 50 Having thus described my invention what I claim as new and desire to secure by United States Letters Patent is:—
1. A bomb dropping device, comprising a container for bombs, brackets mounted thereon, supports with extensions slidably mounted in the brackets, pairs of bomb engager members movably mounted on the supports and extensions, springs connected between the said pairs of members for clamping bombs in 55 loaded position when the engager members are extended and for retracting the engager members into collapsed positions upon a discharge of the said bombs, means for urging the said supports so that the engager members are extended and means for moving the 60 65

2. In a bomb dropping device, a pair of bomb engager members pivotally mounted on a support and extension therefrom, and arranged for engaging on the top and bottom of a bomb when in an extended position, and a spring connected between the said pair of members for clamping a bomb in a loaded position when the engager members are extended and for retracting the engager members into a collapsed position upon a discharge of the said bomb. 70 75

In testimony whereof I have affixed my signature.
